US00D821702S

(12) United States Design Patent (10) Patent No.: US D821,702 S
(45) Date of Patent: * Jul. 3, 2018

(54) BRASSIERE

(71) Applicant: Victoria's Secret Stores Brand Management, Inc., Reynoldsburg, OH (US)

(72) Inventors: Erin Krasner, New York, NY (US); Heather Sperber, Brooklyn, NY (US)

(73) Assignee: Victoria's Secret Stores Brand Management, Inc., Reynoldsburg, OH (US)

() Term: 15 Years

(21) Appl. No.: 29/614,927

(22) Filed: Aug. 24, 2017

(51) LOC (11) Cl. 02-02

(52) U.S. Cl. D2/708

(58) Field of Classification Search

USPC D2/706, 707, 708, 709, 710, 840

CPC A41C 3/00

See application file for complete search history.
